CLAIM

The ornamental design for a LED LIGHT, as shown and described.

DESCRIPTION

FIG. 1 is a front, top perspective view of a LED LIGHT showing a first embodiment of my design;

FIG. 2 is a back, bottom perspective view of the first embodiment;

FIG. 3 is a front view of the first embodiment;

FIG. 4 is a back view of the first embodiment;

FIG. 5 is a left side view of the first embodiment;

FIG. 6 is a right side view of the first embodiment;

FIG. 7 is a top view of the first embodiment;

FIG. 8 is a bottom view of the first embodiment;

FIG. 9 is a front, top perspective view of a LED LIGHT showing a second embodiment of my design;

FIG. 10 is a back, bottom perspective view of the second embodiment;

FIG. 11 is a front view of the second embodiment;

FIG. 12 is a back view of the second embodiment;

FIG. 13 is a left side view of the second embodiment;

FIG. 14 is a right side view of the second embodiment;

FIG. 15 is a top view of the second embodiment;

FIG. 16 is a bottom view of the second embodiment;

FIG. 17 is a front, top perspective view of a LED LIGHT showing a third embodiment of my design;

FIG. 18 is a back, bottom perspective view of the third embodiment;

FIG. 19 is a front view of the third embodiment;

FIG. 20 is a back view of the third embodiment;

FIG. 21 is a left side view of the third embodiment;

FIG. 22 is a right side view of the third embodiment;

FIG. 23 is a top view of the third embodiment; and

FIG. 24 is a bottom view of the third embodiment.

All broken lines represent portions of the LED LIGHT that form no part of the claimed subject matter.
